Primary Examiner — Jeffrey D Asch*Assistant Examiner* — Tracey J Bell(74) Attorney, Agent, or Firm — Eric Kelly(57) CLAIM

The ornamental design for an ornament, as shown and described herein.

DESCRIPTION

FIG. 1 illustrates a top perspective view of an ornament, showing our new design;

FIG. 2 illustrates a bottom perspective view thereof;

FIG. 3 illustrates a front or a back view thereof (note, such front and back views are symmetrical);

FIG. 4 illustrates a right-side view thereof;

FIG. 5 illustrates a top view thereof;

FIG. 6 illustrates a bottom view thereof; and,

FIG. 7 illustrates a left-side view thereof.

The broken lines in the figures depict portions of the ornament that form no part of the claimed design.
